SPRINKLING HOSE SUPPORT

Charles B. Day, Colorado Springs, Colo.

Application November 18, 1946, Serial No. 710,530

2 Claims. (Cl. 248—85)

1 This invention relates to improvements in sprinkling hose supports.

In cities where it is customary to irrigate the lawns during the summer season, it frequently becomes necessary to sprinkle a certain place for a considerable length of time and with the ordinary sprinkling nozzle this is usually accomplished by some one holding the hose, which is a time consuming and tedious task.

I am aware that various devices have been invented and patented for holding the sprinkling hose in a given position. Such devices, however, are usually quite complicated of structure and expensive to manufacture with the result that they are not very widely employed.

It is the object of this invention to produce a simple substantial and convenient device for holding the sprinkling hose, which device can be readily adjusted into any desired position and which will retain the position into which it has been adjusted.

Another object of this invention is to produce a device of the class mentioned which shall be so designed that it may be constructed with a minimum amount of special tools and which can be manufactured at a comparatively low cost.

A further object is to produce a device that will have such a construction that the relatively movable parts will remain in adjusted position due to a construction that provides sufficient friction to hold them in adjusted position.

The above and other objects that may become apparent as this description proceeds are attained by means of a construction and an arrangement of parts that will now be described in detail and for this purpose reference will be had to the accompanying drawing in which the invention has been illustrated in its preferred form, and in which:

Figure 1 is a top plan view of the device;

Figure 2 is a side elevation looking upwardly in Figure 1;

Figure 3 is a section taken on line 3—3, Figures 1 and 2;

Figure 4 is a fragmentary bottom plan view partially in section taken on line 4—4, Figure 2; and

Figure 5 is a section through the hose holding clamp, showing a slightly modified form of construction.

In the drawing reference numeral 10 designates a round plate of sheet metal of suitable thickness. This plate has a central opening indicated by 11, in Figure 3, for the reception of a rivet 12. Secured to the under surface of plate

10 are two pairs of legs, each pair being designated by reference numeral 13. These legs are interconnected by a curved piece 14 in the manner shown in Figure 4 and are preferably spot-welded to plate 10. The curved section 14 gives a stable base for the legs and resists transversely acting forces. The spotwelding may be at any suitable place along the curved part 14. The function of legs 13 is to penetrate the ground and to hold the apparatus in a predetermined adjusted position.

Supported on plate 10 is a plate 15 that has an upwardly dished center section 16 terminating in a substantially flat flange 17. Plate 15 is curved upwardly forming a vertical support 18 that is provided with an opening 19 for the reception of rivet 20. Secured to one side of plate 19 by means of the rivet 20, is a circular plate having a substantially flat rim 21 and a dished central portion 22. Rivet 20 extends through plates 18 and the central portion 22 and the parts are held so that the flange 17 is pressed against the adjacent surface of plate 18 with sufficient force to provide a substantial amount of frictional resistance against rotation. Secured to the outer surface of center portion 22 is a trough-like member 23 that is of the proper size to receive and support a hose 24 that has been indicated by dotted lines in Figures 2 and 5. When rivet 20 is put into position, it is riveted to such an extent that the flange 17 is forced against the upper surface of plate 10 with sufficient force to produce a frictional resistance that holds the parts in adjusted position.

35 The trough-like member 23 may be of any suitable shape but in Figure 5 a cross section has been shown of a slightly modified trough which has been designated by reference numeral 23a. It will be seen that this has an inwardly curved portion 25 that serves to hold the hose in position. Any other suitable means may be provided. The hose supporting trough 23 must be of such construction and design that it will serve as a suitable support for the hose and hold the latter against accidental movement due to slight forces.

50 With the construction above described and shown on the drawing, a support is formed that, first of all, can be securely fastened to the ground surface by pushing the legs 13 into the soil to whatever depth is desired. The hose is then positioned in the trough and adjusted rotatably about pivot 12 and in a vertical angle by movement of the trough about rivet 20. After the hose has been adjusted, it can be left for any length of time, but the adjustment can be quickly changed

3

by applying the slight force necessary to rotate the adjustable members about their pivots which, in this case, are formed by the two rivets.

Due to the use of cup members against flat surfaces, the use of springs or nuts to maintain and vary the tension can be dispensed with. The material naturally has some resiliency and with the construction shown, when properly assembled, the adjustable members are urged into frictional engagement by their respective supports by means of a resilient force that will remain effective throughout the entire life of the apparatus. If, for any reason, the frictional resistance should become too small, it can be quickly increased by applying a few hammer strokes to the rivets to further shorten them.

In the drawing the parts have been shown rounded as this gives the most pleasing appearance, but it is to be understood that plate 10 and also plate 15 can be of any shape desired.

Since the entire device is constructed from sheet metal and since the parts can be readily cut by dies and formed by suitable dies and since the assembling of the device merely requires spotwelding trough 23 to the center portion 22, the labor involved in assembling the device is comparatively small. Instead of spotwelding the trough to the center portion 22, it may be applied by rivets or in any other suitable way.

Having described the invention what is claimed as new is:

1. A sprinkler hose support comprising, in combination, a horizontal plate having a plurality of legs projecting from its under surface for insertion into the ground, the plate having a central opening for the reception of a pivot, a supporting bracket formed from a metal plate hav-

ing two right angularly related sections, each section having an opening for a pivot, one of said sections being concave on its under surface and rests on the plate, means comprising a pivot pin for rotatably interconnecting the bracket with the plate, a spherically concave disk pivotally connected with the vertical side of the bracket, and a hose supporting trough secured to said disk.

2. A sprinkler hose support comprising in combination, a bracket formed from a sheet metal plate bent into two right angularly related sections, each of which has a hole for a pivot pin, a horizontal plate having a plurality of legs on its under surface for insertion into the ground, said plate having a hole for a pivot pin, one of the sections of the bracket being concave on its outer surface, said last named portion resting on the horizontal plate, a pivot pin forming means for rotatably interconnecting the bracket and the plate, a disk having one side concave fitted against the vertical surface of the bracket, a pivot pin interconnecting the concave disk and the bracket for relative rotary movement, and means on the concave disk for supporting a sprinkler hose.
